CLAIM

The ornamental design for a shelving bracket, as shown and described.

DESCRIPTION

FIG. 1 is a top, front perspective view of the shelving bracket, having a first and a second end;

FIG. 2 is a bottom perspective view of the shelving bracket, having a first and a second end;

FIG. 3 is a side view of the first end of the shelving bracket;

FIG. 4 is a side elevation view of the second end of the shelving bracket;

FIG. 5 is a bottom view of the second end of the shelving bracket;

FIG. 6 is a bottom view of the first end of the shelving bracket;

FIG. 7 is a top view of the second end of the shelving bracket; and,

FIG. 8 is a top view of the first end of the shelving bracket. It is understood that FIGS. 3-8 are enlarged fragmentary views for clarity of disclosure.

The surface shading on the illustrated shelving bracket is intended only to show the character and contour of the surfaces and not surface indicia.
